CLOTH FEEDING MECHANISM FOR COMBI-
NATION TEA BAG MACHINESLouis Hirschhorn and Hans Irmscher, New York,
N. Y., assignor to Millie Patent Holding Co.
Inc., New York, N. Y., a corporation of New York

Application May 28, 1932, Serial No. 614,090

19 Claims. (Cl. 112—10)

The present invention relates to machines for forming bags from a continuous source of material and embodies, more specifically, an improved mechanism for feeding a continuous supply of cloth or other material to a device for severing lengths thereof and sewing the same in such manner as to form a plurality of bags which are open at one end.

In certain manufacturing operations, particularly in the manufacture of bags for tea and other substance from which the essence is to be extracted, the bags are quite small in size and must be manufactured in great quantities. To facilitate the manufacture of these bags, machines have been constructed into which are fed rolls of cloth or other suitable material which have previously been formed into continuous sleeves by folding the cloth over and sewing the outer edges thereof at one side. In existing machines, the manipulation of these rolls of cloth to feed the same into cutting and sewing mechanisms has been the subject of considerable attention in as much as it is desirable to dispense entirely with manual supervision. This necessitates an apparatus which will correctly feed and position the cloth with respect to a cutting mechanism and subsequently carry the severed portions thereof to a sewing machine. After the sewing operation, the open bag should be automatically turned inside out and filled. The number and nature of these operations, to be entirely automatic places a considerable premium upon an efficiently designed mechanism which functions accurately and effectively in order that no single operation may fail and thus impair the functioning of the entire mechanism.

To improve the present forms of cloth feeding and bag forming mechanisms, the present invention has been designed and it is an object of this invention to provide a cloth feeding mechanism which effectively advances a continuous sleeve of cloth or other material to a cutting and sewing machine in such fashion that the material is moved in an improved manner to insure a more effective and positive handling thereof.

A further object of the invention is to provide a cloth feeding mechanism which maintains a predetermined slack from a source of material, such as a reel of cloth or a spool upon which a continuous sleeve has been wound.

A further object of the invention is to provide a cloth feeding mechanism wherein an improved device has been embodied to create a desired amount of slack in the supply of material which is fed.

A further object of the invention is to provide a

cloth feeding mechanism wherein the material is fed to a cutting mechanism in the form of a sleeve, the sides of which are separated in order that a severed length of the sleeve may be held from within by a device which carries the severed portion to a continuously operating sewing machine. 5

A further object of the invention is to provide an improved cloth feeding mechanism by means of which a continuous sleeve of cloth or other material is fed in measured and variable quantities to a cutting mechanism, the feeding mechanism being of an improved and positive nature whereby the lengths of the portions severed from the sleeve are accurately maintained and the severed portions are effectively handled in subsequent operations. 10

A further object of the invention is to provide a cloth feeding and bag forming mechanism wherein severed portions of a sleeve of suitable material are handled in an improved fashion during the operation of sewing the severed portions across one end thereof. 20

Further objects, not specifically enumerated above, will be apparent as the invention is described in greater detail in connection with the accompanying drawings, wherein:

Figure 1 is a view in end elevation showing a cloth feeding and cutting mechanism constructed in accordance with the present invention.

Figure 2 is a detailed view in section, taken in a plane parallel to that of Figure 1 and looking from the opposite direction, showing the improved mechanism for forming slack in the material supplied to the feeding mechanism. 30

Figure 3 is a detailed view taken from the left in Figure 2, and showing the clamping means for holding the material during a slack forming operation. 35

Figure 4 is a view in section, taken on line 4—4 of Figure 3, and looking in the direction of the arrows.

Figure 5 is a plan view of a short length of a cloth sleeve or tube sewed along one edge which is illustrated in section in Figure 4 and which may be supplied to the feeding mechanism described hereinafter. 45

Figure 6 is a view in section, taken on line 6—6 of Figure 5, and looking in the direction of the arrows.

Figure 7 is a partial plan view showing the supporting and feeding mechanism seen in elevation in Figure 1.

Figure 8 is a partial view in end elevation, showing a cam which is adapted to operate a cutting mechanism and a holding mechanism in 55

such fashion that these mechanisms function in a predetermined sequence.

Figure 9 is a view in section, taken on line 9-9 of Figure 8, and looking in the direction of the arrows.

Figure 10 is a view in end elevation showing a cam which is adapted to actuate fingers for engaging the interior of a severed sleeve section. Figure 11 is a view in section, showing the mechanism for feeding successive lengths of cloth or other continuously supplied material to a cutting mechanism.

Figure 12 is a detailed plan view of the tongue or plate shown in the feeding mechanism of Figure 11.

Figure 13 is a detailed plan view showing the mechanism for feeding lengths of material over fingers which are adapted to hold the same during a cutting and sewing operation.

Figure 14 is a view in section, taken on line 14-14 of Figure 13, and looking in the direction of the arrows.

Figure 15 is a view in end elevation showing the mechanism for cutting lengths of material supplied by the feeding mechanism shown in Figure 11.

Figure 16 is a view in side elevation, showing the operating mechanism for the sewing machine and finger carrying wheel which advances the severed lengths of cloth from the cutting mechanism through the sewing machine.

Figure 17 is a view in section, taken on line 17-17 of Figure 16, and looking in the direction of the arrows, this figure showing the guide fingers for guiding one end of the severed cloth section into the sewing machine.

Figure 18 is a view similar to Figure 17, showing the operation of the guiding device in a direction opposite to that illustrated in Figure 17.

Figure 19 is a plan view showing a bag formed of the severed section of cloth after the same has been sewed across one end thereof.

Figure 20 is a view in end elevation, looking from the right in Figure 16, and showing the finger mounting wheel, sewing machine and operating mechanism therefor.

Figure 21 is a view in end elevation showing the arms by means of which the material is engaged and guided during the sewing operation.

With reference to the accompanying drawings, the frame of a machine constructed in accordance with the present invention is illustrated at 1 and is provided with a suitable source of power which is connected to a power shaft 2 which may be journaled upon the frame in bearings 3. A bracket 4 is mounted upon the frame and receives a spool 5 upon which a continuous sleeve of material may be wound in accordance with present practice.

Material from the spool 5 is fed to a cutting mechanism indicated at 6 in Figure 1 and described in detail hereinafter. From the cutting mechanism, the severed lengths of material are carried to a sewing machine 7 (Figure 16) by means of fingers 58 and 59 upon which the material is fed prior to cutting. Fingers 58 and 59 move outwardly against the sides of the section to be cut and thus frictionally hold the same during the movement of such sections through the sewing machine and to a subsequent device for inverting and filling the bags so formed.

In order that the material may be fed in predetermined lengths to the cutting mechanism 6, a reciprocating head or frame 9 is provided, the frame being slidably mounted upon slide bars 10

and 11 (Figure 1). Frame 9 carries an idle supporting roller 12 and a feed roller 13, the operation of which will be described in detail subsequently. Over the rollers 12 and 13, a metal plate or tongue 14 is placed, the material being drawn over the plate so that the latter is always enclosed by the material and guides the same effectively during its movement to the cutting mechanism.

In order that all tension in the material may be eliminated during the reciprocation of the frame 9, a slack forming device is provided which acts upon the material from the reel to create a desired slack therein without tensioning the festoon of material between the slack producing device 15 and the plate or tongue 14.

Referring specifically to Figure 2, the material from the reel is indicated as festooned at 15 and passes to the tongue or plate in a festoon 16. During movement of the frame 9 to the left, as viewed in Figure 1, the material is clamped against movement by means of a clamping head 17 and the slack producing device functions. In Figures 3 and 4, the clamping head will be seen as being formed of spaced guide members 18 within which guide slots 19 are formed. Slots 19 receive a guide rod 20 which is formed with a partially squared section 21. A bottom plate 22 on the clamping head 17 is provided with slide rods 23 which are mounted slidably in the bottom plate 22 and are secured to a presser foot 24. Springs 25 normally urge the presser foot upwardly and thus adapt the same to engage the bottom of the partially squared section 21 yielding when the clamping head 17 is moved upwardly. Presser foot 24 thus forms a guide member over which the material passes to festoon between the plate or tongue 14 and the reel 5.

The upward movement of the head 17 is effected by means of a link 26 which is provided with a fitting 27 which is journaled upon a cross rod 28 secured between the side plates 18 of the head 17. Link 26 is pivoted to an arm 29 which is journaled upon a bracket 30 and formed with a roller 31 which is engaged by an operating cam 32 upon the power shaft 2. After the clamping head 17 has been actuated to secure the material against movement, an arm 33 is actuated to form a sufficiently deep festoon 15 in the following manner. Arm 33 is pivoted at 34 upon the frame of the machine and is provided with a guide rod 35 over which the material passes in moving to the clamping head 17. A link 36 is pivoted to the arm 33 and to an extension of the arm 29. Upward movement of arm 29 thus initially actuates the clamping mechanism to prevent movement of the material and subsequently elevates the arm 33 into the position shown in dotted lines in Figure 2 to form sufficient slack in the material. To facilitate the slack forming operation, stationary guide members 37 are formed on the frame of the machine and the arm draws the material between such rods as indicated in dotted lines in Figure 2.

Figures 5 and 6 illustrate one form of material which may be used in connection with devices constructed in accordance with the present invention and the sectional view in Figure 4 illustrates such material passing through the clamping head when the latter is in its released or non-clamping position.

In as much as the material must be fed to the cutting mechanism successively in predetermined lengths, the movement of frame 9 must be properly controlled. Such control is effected by means

of an arm 38 which is journaled at 39 upon a bracket 40. Arm 38 is provided with a roller 41 which engages a cam 42 upon power shaft 2. A spring 43 maintains the roller 41 in engagement with the surface of the cam and arm 38 is thus swung pivotally back and forth about the pivot mounting 39. An arcuate slot 44 (Figure 11) is formed in the arm 38, the radius of this slot extending from a hinge point 45 to which a connecting rod 46 is connected. Rod 46 is mounted at its other end in the slot 44 and by means of a clamp 47, the position of the end of the rod 46 in the slot may be varied. In this manner, the throw of the connection and consequently the extent of movement of the rod 46 in a horizontal plane may be varied. Since the rod 46 is connected to the frame 9, reciprocation of the latter upon the slide rods 10 and 11 is effected.

As the frame 9 moves to the right, as viewed in Figures 1 and 11, the material in which the plate or tongue 14 has been threaded will pass over such tongue in a relative direction to the left as viewed in Figures 1 and 11. In as much as this connection produces literally a dragging of the material over the tongue and rollers, it is desirable to impart a festoon feed to the material at the roller 13 where the greatest change of direction takes place. This is accomplished by forming the roller 13 with a circular groove 48 over which a flexible belt or cord 49 passes (see Figure 7). The left hand end of the belt 49, as viewed in Figures 1 and 11, is anchored at 50 while the other extremity of the belt is connected to a spring 51 (Figures 1 and 11) which places a predetermined tension upon the belt. Ratchet teeth 52 are formed upon the roller 13 and a pawl 53 is mounted upon an arm 54 which is carried by the frame 9. When the frame 9 moves to the right, as viewed in Figures 1 and 11, the roller passes along the belt 49 and is thus rotated at a speed equal to that at which the material passes over the tongue 14. When the frame moves to the left, as viewed in Figures 1 and 11, the pawl 53 engages the ratchet teeth 52 to prevent reverse rotation of roller 13 and the belt 49 is thus dragged over the groove 48. A roller 55 is mounted upon a frame 56 and engages the tongue 14 and the material thereon and holds the same in position upon the rollers 12 and 13.

The end of tongue 14 is formed with outwardly flaring spring arms 57 in order that the sides of the sleeve of material may be separated when they are advanced on to supporting fingers described hereinafter. Figure 12 illustrates the tongue in plan view while Figure 11 shows the spring arms which function as described above. When the frame 9 is moved to the left, as viewed in Figure 20, the end of the material is moved over cooperating supporting fingers 58 and 59 which are journaled at 60 and 61, respectively, upon a wheel 62. Figures 13, 14 and 15 illustrate the construction and operation of the supporting fingers, while the wheel is illustrated in Figures 1, 15, 16, and 20. In actual practice, the wheel 62 is formed with a plurality of pairs of supporting fingers 58 and 59 but in the interest of clearness only one pair of such fingers is shown and described herein.

The supporting fingers are formed with arms 63 between which a spring 64 is connected in order that the ends of the fingers may be normally urged away from each other to engage the sides of the material from within. Movement of the fingers is synchronized by means of a connection therebetween, such connection being provided

in the form of arms 65 and 66 upon the respective fingers 58 and 59. Arm 65 is formed with a recess 67 into which a tooth or projection 68 on the arm 66 extends. Finger 59 is formed with a cooperating arm 69 which is adapted to be engaged by an actuating plate 70, seen in Figures 1, 13, 14 and 15. Plate 70 is mounted upon an arm 71 which is pivoted at 72 and formed with an extension 73 which engages a cam on the power shaft 2. A spring 74 normally urges the plate 70 away from the arm 69 and holds the extension 73 upon the surface of the operating cam. When the cam actuates the extension 73 to move the plate 70 to the right, as viewed in Figure 1, the arm 69 is engaged and the supporting fingers 58 and 59 are moved into the position shown in Figure 13. At this time, the frame 9 is moved to the left as viewed in Figures 1 and 11 and the material is advanced over the supporting fingers, in the manner illustrated in Figure 13. Spring 20 arms 57 will thus be seen to insure the separation of the sides of the material in order that the supporting fingers may be received therein. Further movement of the operating cam retracts plate 70 from arm 69 and enables spring 64 to move the 25 fingers 58 and 59 outwardly to engage the sides of the material. Figures 15 and 20 illustrate the position of the supporting fingers at such time.

In order that the material may be securely held upon the supporting fingers 58 and 59 during the time in which the frame 9 moves to the right as viewed in Figures 1 and 11, a presser foot 75 (Figure 15) is actuated to engage the material and force the same against the under-side of the supporting fingers 58 and 59. Presser 30 foot 75 is mounted upon rods 76 which are slidably mounted upon a lever 77 which is journaled at 78 and provided with an extension 79 having a roller 80 which engages a cam surface 81, formed upon a cam member 82. This cam member is 40 illustrated in detail in Figures 8 and 9 and serves as the actuating member for the presser foot 75, as well as the cutting mechanism which will be described presently. The cam member 82 is mounted upon power shaft 2 (Figure 1) and thus 45 moves the presser foot 75 into engagement with the material under the supporting fingers 58 and 59 to secure the material thereon. A spring 77' serves to move the arm 71 and presser foot 75 away from the supporting fingers and to move 50 the roller 80 against the cam surface 81. After the presser foot 75 has engaged the material the frame 9 moves to the right, as viewed in Figures 1 and 11 and the spring arms 57 are retracted from their position as shown in Figure 13 in order that they may clear the cutting mechanism 55 6. At such time, the cutting mechanism is actuated to sever a predetermined length of material from the material upon the tongue 14.

The cutting mechanism comprises a pair of 60 blades which are hinged at 83 to form a shearing device, one of the elements being mounted upon an arm 84 and another upon an arm 85. Arm 84 is connected to an arm 86 through a lost motion connection 87 while arm 85 is connected to an 65 arm 88 through a link 89 (Figure 15). Each of the arms 86 and 88 is formed upon a common actuating member 90 which is secured to a shaft 91 upon a bracket 92 and the member 90 is operated by means of the peripheral cam surface upon cam member 82. This surface engages a roller 92' which is mounted upon an arm 93, journaled upon a bracket 93' at 94. To the other end of arm 93 is pivoted a bifurcated member 95, a similar bifurcated member 96 being pivoted upon a rod 97 75

- which is secured to the member 90 (Figure 1). A link 98 is connected between the bifurcated members 95 and 96 and thus the movement of arm 93 is transmitted to the shearing mechanism 6. 5 The shearing mechanism is normally maintained in the opened position as seen in Figure 15 by means of a spring 90' which engages an arm 91' secured to shaft 91.

After the cutting operation has been completed 10 the presser foot 75 is withdrawn from its holding position and the wheel 62 is turned to position a subsequent pair of supporting fingers in the position illustrated in Figure 15. The movement of wheel 62 is effected by means of gear teeth 99 which 15 are formed thereon and which are engaged by a driving pinion 100. Pinion 100 thus forms a driving connection between the wheel 62 and the frame of the sewing machine 7 to cause the movement of the frame of the sewing machine to be transmitted to the wheel when such frame is actuated by a device described hereinafter. Periodic movement of the frame of the sewing machine thus is transmitted to the wheel 62 and during the interval of pause between successive frame 20 actuations, the driving connection between pinion 100 and gear 99 permits the frame of the sewing machine to be moved with respect to the wheel 62 in order that the sewing operation may take place to sew one end of the severed portion of the 25 material which is mounted upon the corresponding supporting fingers 58 and 59. Pinion 100 is driven by mechanism described as follows. Pinion 100 is mounted upon a shaft section 101 which is journaled in a bracket 102. A universal connection 103 is provided between the shaft section 101 and a shaft 104 which is driven by a shaft section 105 being connected thereto by a universal joint 106. The shaft section 105 is journaled in bearings 107 which are formed upon a bracket 108 30 mounted upon the frame of the machine. Upon an overhanging portion of the shaft 105 a sprocket wheel 109 is mounted, the sprocket wheel being driven by means of a chain (indicated in dot and dash lines in Figure 16) which is driven by a driving sprocket 110. Driving sprocket 110 is mounted upon a shaft 111 which is driven by a bevel gear 112 which is connected to a driving bevel gear mounted upon power shaft 2.

The sewing machine 7 is mounted upon a frame 50 113 (Figures 16 and 20) which is journaled upon a shaft 114 concentric with the wheel 62. Frame 113 is provided with a bracket 115 upon which the bearing 102 is formed. The frame 113 is reciprocated by means of a link 116 which is pivoted thereto at 117 and connected to a lever 118 55 which is journaled between arms 119, mounted upon the frame of the machine. Lever 118 is provided with a roller 120 which engages a cam 121, mounted upon power shaft 2 (Figures 16 and 20). When link 116 is elevated by the cam 121 the frame 113 and sewing machine 7 are moved in a clockwise direction about shaft 114 as viewed in Figure 20. Such movement is transmitted through the pinion 100 and gear 99 to the wheel 62 to position a subsequent pair of fingers in front 60 of the cutting mechanism and the frame 113 upon which the sewing machine is mounted is moved about the wheel 62 in a counter-clockwise direction by means of the rotation of shaft 104 which is imparted to the pinion 100 and gear 99. Such rotation feeds the sewing machine into the material supported upon the fingers 58 and 59 and effects the sewing of one end thereof as illustrated in Figure 19. In as much as shaft 104 rotates continuously, there will always be a relative move- 70 75

ment between the sewing machine frame 113 and the wheel 62, in order that the sewing machine may sew continuously and that its operation may not be impaired.

The sewing machine is driven by a belt 122 which passes over idler pulleys 123 and 124. Pulleys 124 are mounted upon a frame 125 which is pivoted at 126 and maintains a predetermined tension in the belt by means of a spring 127. The belt is mounted over a driving pulley 128 10 which is secured to a shaft 129 and driven by a gear wheel 130 which engages a gear 131 upon the shaft 129. Wheel 130 is mounted upon a shaft 132 which is driven by a bevel gear connection 133 upon power shaft 2 (Figure 20). 15

In order that the wheel 62 may be maintained in fixed positions during the sewing and cutting operations, a flange 134 is formed thereon and provided with a plurality of spaced notches 135 corresponding in number to the number of pairs of supporting fingers mounted thereon. Notches 135 are engaged by a spring-pressed finger 136 to hold the wheel against motion during the foregoing operations. During the upward motion of link 116 the spring of detent 136 is overcome and the 20 detent rides out of a notch and upon the surface of flange 134 to engage a subsequent notch. 25

When the cut sections are moved into the sewing machine, it is necessary that the sides thereof be placed together in the position in which they 30 are to be sewed. A device for effecting such condition is illustrated in detail in Figures 17 and 18, and the operating mechanism therefor is illustrated in Figures 16 and 20. This device comprises a stationary back plate 137 which is secured to a 35 bracket 138, carried by the sewing machine frame 113. The bracket 138 pivotally mounts an arm 139 at 140, an extension 141 of the arm 139 being adapted to be engaged by a detent 142 which is secured to the link 116 as seen in Figures 16 and 40 20. Arm 139 is provided with a bifurcated upper extremity and is adapted to engage the material upon the supporting fingers and move the same against the backing plate 137 as illustrated in Figures 17 and 18. The bifurcated extension permits the sewing mechanism to advance over the material and thus insures that the sides of the material are in the proper position when the sewing needles advance into engagement therewith. 45

It will thus be seen that a cloth feeding and 50 bag forming machine has been provided which effectively controls the movement of material from a continuous supply to a cutting mechanism and subsequently to a sewing machine for forming bags. 55

While the invention has been described with specific reference to the accompanying drawings, it is not to be limited, save as defined in the appended claims.

We claim as our invention:

1. In combination with means for acting upon a material and means to supply material, guide means for directing material from the supply to the first means, a presser foot cooperating with the guide means and adapted to engage material between the foot and guide means, a slack producing arm adapted to engage material between the presser foot and supply, and means to actuate the presser foot and arm simultaneously. 60

2. In combination with means for acting upon a material and means to supply material, guide means for directing material from the supply to the first means, said guide means including a reciprocable head having spaced sides slidably 65 70 75

- mounted upon a squared shaft, a presser foot slidably mounted on the head and adapted to engage the shaft yieldingly, means to limit the movement of the presser foot toward the shaft, 5 and means to move the head slidably upon the shaft to bring the presser foot against the shaft.
3. In combination with means for acting upon a material and means to supply material, guide means for directing material from the supply 10 to the first means, said guide means including a reciprocable head having spaced sides slidably mounted upon a squared shaft, a presser foot slidably mounted on the head and adapted to engage the shaft yieldingly, means to limit the movement of the presser foot toward the shaft, 15 an arm adapted to engage material between the presser foot and supply to form slack therein, and means to move the head slidably upon the shaft to bring the presser foot against the shaft, 20 and subsequently to actuate the arm.
4. Means for acting upon material, guide means for directing material to the first means, means to move the guide means and material toward the first means, means to move the guide means 25 away from the first means, and positive driving means to engage the material and move the same over the guide means during movement of the guide means away from the first means.
5. Means for acting upon material, a guide 30 plate for directing material to the first means, a frame slidably mounted with respect to the first means, means on the frame for supporting the guide plate thereon, means to move the frame slidably, and means to move the material over the guide plate.
6. Means for acting upon material, a guide 35 plate for directing material to the first means, a frame slidably mounted with respect to the first means, rollers on the frame to support the guide plate thereon, means to move the frame slidably, and means to turn one of the rollers.
7. Means for acting upon material, a guide 40 plate for directing material to the first means, a frame slidably mounted with respect to the first means, rollers on the frame to support the guide plate thereon, means to move the frame slidably, and means to turn one of the rollers simultaneously with the sliding of the frame away from the first means.
8. Means for acting upon material, a guide 45 plate for directing material to the first means, a frame slidably mounted with respect to the first means, rollers on the frame to support the guide plate thereon, means to move the frame slidably, means to turn one of the rollers simultaneously with the sliding of the frame away from the first means, and means to prevent turning movement of the said one roller in the opposite direction.
9. Means for acting upon material, a guide 50 plate for directing material to the first means, a frame slidably mounted with respect to the first means, rollers on the frame to support the guide plate thereon, means to move the frame slidably, and means to turn one of the rollers simultaneously with the sliding of the frame away from the first means at a peripheral speed equal to the speed of motion of the frame.
10. Means for acting upon material, a guide 55 plate for directing material to the first means, a frame slidably mounted with respect to the first means, rollers on the frame to support the guide plate thereon, means to move the frame slidably, means to turn one of the rollers simultaneously with the sliding of the frame away from the first means, and a ratchet and pawl mechanism between the frame and said one roller to prevent turning of the said roller in one direction.
11. Means for acting upon material, a guide 60 plate for directing material to the first means, a frame slidably mounted with respect to the first means, rollers on the frame to support the guide plate thereon, means to move the frame slidably, a flexible member anchored at one end and secured at the other end to a resilient member, said flexible member passing over one of the rollers, and a ratchet and pawl mechanism between the frame and said one roller to prevent turning of said roller in one direction. 65
12. Means for acting upon material, a guide plate for directing material to the first means, a frame slidably mounted with respect to the first means, rollers on the frame to support the guide plate thereon, means to move an operating member adapted to be moved in opposite directions, a link between the frame and operating member, and means to adjust the connection between the link and member to vary the extent of movement of the frame. 70
13. Means for acting upon material, a guide plate for directing material to the first means, a frame slidably mounted with respect to the first means, rollers on the frame to support the guide plate thereon, means to move an operating lever formed with an arcuate slot, and a link connected to the frame and adjustably connected to the slot. 75
14. Means for acting upon material, a guide plate for directing material to the first means, a frame slidably mounted with respect to the first means, rollers on the frame to support the guide plate thereon, means to move a link pivotally connected to the frame, and a pivoted reciprocable operating lever formed with a slot curved about the pivoted connection of the link to the frame, and receiving the other end of the link adjustably. 80
15. In combination with a wheel provided with a plurality of pairs of arms adapted to receive cut lengths of material, a cutting device, and means to supply material to the device, means to move the material supplying means toward and away from the cutting device and the arms, means to hold the material upon the arms, and common means to actuate the cutting mechanism and the material supplying means. 85
16. In combination with a wheel provided with a plurality of pairs of arms adapted to receive cut lengths of material, a cutting device, and means to supply material to the device, means to move the material supplying means toward and away from the cutting device and the arms, means to actuate the cutting device between successive movements of the material supplying means, a pressure foot to hold the material upon the arms, means to urge the presser foot against the arms during movement of the material supplying means away from the cutting device, and means to remove the presser foot from the arms during movement of the material supplying means toward the cutting device. 90
17. In combination with a wheel provided with a plurality of pairs of arms adapted to receive cut lengths of material, a sewing machine, a backing plate, a guide member adapted to direct material to be sewed along the backing plate and into the sewing machine and means to move the guide toward and away from the backing plate, said backing plate and guide member be- 95

ing independent of and located in advance of the sewing machine.

18. In combination with a wheel provided with a plurality of pairs of arms adapted to receive 5 cut lengths of material, a sewing machine, a backing plate, and a guide member adapted to direct material to be sewed along the backing plate and into the sewing machine, said backing plate and guide member being recessed to permit 10 relative movement thereof with respect to the sewing machine whereby the sewing machine may advance into material between the plate and guide member.

19. In combination with a wheel provided with

a plurality of pairs of arms adapted to receive cut lengths of material, a sewing machine, a backing plate and a guide member adapted to direct material to be sewed along the backing plate and into the sewing machine, said backing plate and guide member being recessed to permit relative movement thereof with respect to the sewing machine whereby the sewing machine may advance into material between the plate and guide member, and means to move the guide member with respect to the plate. 10
